UNITED STATES PATENT OFFICE.

RASMUS HANSEN, OF SIOUX CITY, IOWA, ASSIGNOR OF ONE-HALF TO INTERSTATE SUPPLY COMPANY, OF SIOUX CITY, IOWA, A CORPORATION OF IOWA.

SUBSTATION TELEPHONE SET.

No. 916,552.

Specification of Letters Patent. Patented March 30, 1909.

Application filed December 9, 1907. Serial No. 405,641.

To all whom it may concern:

Be it known that I, RASMUS HANSEN, a subject of the King of Denmark, and a resident of Sioux City, county of Woodbury, and 5 State of Iowa, have invented a new and useful Improvement in Substation Telephone Sets, of which the following is a specification.

My invention pertains to equipments for telephone substations and has as its object 10 the production of a wall set having the following advantages: minimum size of case for the apparatus to be mounted; a writing shelf of maximum size; location of writing shelf convenient for the hand of a person 15 using the transmitter; accessibility of parts of apparatus when the door of the case is open; a transmitter circuit contained wholly within the body of the cabinet and not involving flexible conductors attached to the 20 door of the cabinet. I secure these advantages by the use of a cabinet box substantially parallelepipedonal, the front of which is closed by a swinging door; within the open box body I mount all apparatus except the 25 ringer. The door to the box is of such construction as to provide a writing shelf, and for the purpose of securing a desirable slope in the writing shelf without unduly increasing the thickness of the door, the upper for- 30 ward edge of the box body may be truncated as shown at 2' in the figures. The ringer I mount within the space contained between the back surface of the writing shelf and the plane of the front edges of the box body; in 35 this mounting no space within the box body is required or reserved for the ringer or for any portion thereof, and a further advantage is gained in that when the door is open at ninety (90) degrees, as in Fig. 2, the ringer 40 does not project in front of the box body to interfere with the hand of a workman engaged upon the box body or contents whereby by the workman might be handicapped or the ringer injured. The writing shelf is 45 made of maximum size, substantially occupying the entire front of the door. The transmitter I mount upon the side of the box body, by which expedient I do not sacrifice any writing-shelf space nor am I obliged to 50 extend the backboard of the box to provide space for the transmitter, while at the same time a rigid mount for the transmitter admitting of rigid wiring of the local circuit is obtained, and the transmitter itself occupies 55 a space immediately above the switchhook

and thus does not occupy space either on the wall or in a packing box in excess of that required by the substation set with the usual projecting switchhook.

In the drawings, Figure 1 shows an isometric perspective of the device, and Fig. 2 shows front elevation with the door of the device open at an angle of ninety (90) degrees, the door being shown in section to reveal the contained ringer in elevation. 60

Upon the backboard 1 the box 2 is permanently mounted, the plane door 3 being hinged thereto. The door 3 carries an inclined shelf 4 with rib 4', the plane door and the writing shelf being united by side braces 70 5 and bottom brace 6. The plane door is cut away between the side braces above the bottom brace to give access to the ringer 7 which is mounted upon the bottom brace in such manner that it lies wholly within the space 75 in front of the plane of the back surface of the plane door.

The box body has a shelf 8 supporting the batteries 9. The space above and below the shelf 8 is available for generator hook switch 80 and induction coil. Transmitter 10 is mounted upon the side of the box body at the left end near the top, the bracket used being an ordinary transmitter arm 11 mounted upon a plate 12 so that the plane of the 85 base of the plate 12 is parallel to the plane of movement of the extending arm 11. This location of the transmitter support upon the side of the box gives a minimum length of primary circuit wiring to include the hook 90 switch, induction coil 13, the batteries 9—9 and transmitter 10 without requiring an extended backboard for the transmitter and without restricting the size of the writing shelf. Furthermore, by this position of the 95 transmitter at the side of the cabinet the writing shelf lies relatively to the right of the transmitter where it is more convenient to the right hand of a telephone patron.

Heretofore two methods of mounting the 100 transmitter on a telephone wall set have been known, viz., to mount the transmitter upon a long arm attached to a plate upon the backboard, the long arm bringing the transmitter forward beyond the cabinet of the set; 105 and second, to mount the transmitter upon a plate by means of a knuckle joint or hinge, the plate being mounted upon the face of the cabinet of the set. The first method gave a very desirable range of vertical ad- 110

justment to the transmitter by swinging it vertically on a hinge at the base of the arm, whereby the transmitter might be brought to a height suitable for convenience of different speakers without causing the plane of the diaphragm to vary to any considerable extent from the vertical, owing to the relatively long radius of the transmitter arm. The second method is objectionable by reason of the lack of adjustment in the transmitter, as a very slight movement vertically varies the plane of the diaphragm accordingly. Heretofore it has been necessary to provide additional backboard space for the transmitter in order to obtain the desirable feature of vertical transmitter adjustment as it has been accepted as objectionable to mount the long-arm transmitter upon the face of the cabinet, thus causing it to project into the room to an undesirable extent. My design of cabinet and side-arm transmitter support secure the advantages of a long-arm transmitter having a maximum vertical adjustment, economizing backboard space and therefore wall space, leaving the face of the cabinet free for writing shelf and being at the same time within the usual limits of projection from the wall into the room. A further advantage has been mentioned in the feature of throwing the transmitter to the left of the writing shelf rather than above it.

Above the induction coil 13 I install a terminal clip 14 to which I attach the secondary winding of the induction coil. The object of this additional terminal clip is to provide convenience for condenser connections in case it is desired to include a condenser in

series with the secondary winding of the induction coil.

By the inclusion of the ringer wholly within the cubic contents of the combined door and writing shelf, it is not required to provide space for the ringer within the body of the cabinet, and a reduction in the size of the cabinet body thus is obtained.

Having thus described my invention, what I claim as new and desire to secure by United States Letters Patent is:

In a substation telephone set, a cabinet box; a backboard therefor slightly larger than the back area of said box; a front therefor and comprising a writing shelf; line binding posts on said backboard; a transmitter bracket mounted upon the side of said box and comprising a base and an arm, said arm projecting from said base in a plane parallel to the mounting face of said base and being pivotally adjustable by movement in said plane whereby a supported transmitter may be raised or lowered; a complete talking circuit completely wired and composed wholly by apparatus elements and connecting wiring contained wholly within or supported directly by the rigid portion of said box; and a ringer carried by said door and located under the writing shelf, substantially as described.

Signed by me at Sioux City, county of Woodbury and State of Iowa in the presence of two witnesses.

RASMUS HANSEN.
